(57) CLAIM

The ornamental design for a razor, as shown and described.

DESCRIPTION

FIG. 1 is a perspective view of the razor in accordance with the design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof; and,

FIG. 8 is a preferred application embodiment of the design. The broken line environmental showing is for illustrative purposes only and forms no part of the claimed design.
